UNITED STATES PATENT OFFICE.

HARRISON H. HARMON, OF CLOVIS, NEW MEXICO.

PUMP.

Specification of Letters Patent.

Patented Nov. 3, 1914.

1,116,269.

Application filed October 23, 1913. Serial No. 796,904.

To all whom it may concern:

Be it known that I, HARRISON H. HARMON, a citizen of the United States, residing at Clovis, in the county of Curry and State of New Mexico, have invented certain new and useful Improvements in Pumps; and I do declare the following to be a full, clear, and exact description of the invention, such as will enable others skilled in the art to which it appertains to make and use the same.

This invention relates to pumps, and more especially to those wherein water is elevated by compressed air; and the object of the same is to lift water from great depth with a minimum amount of power. This is accomplished by dividing the total lift into sections and lifting each section by itself independently of any other section—hence the amount of power required for the total lift depends upon the length of each section.

A further object of the invention is to provide means for preventing the interruption of the action of this pump through the sticking of the float as hereinafter described.

These objects are carried out by the mechanism set forth in the following specification and claims, and shown in the drawings wherein—

30 Figure 1 is a longitudinal sectional view of this entire pump, showing the air system in diagram; and Fig. 2 is an enlarged longitudinal vertical section of the uppermost pair of active and idle compartments. Figs. 35 3, 4, 5, are sectional details on the lines 3—3, 4—4 and 5—5 respectively of Fig. 2.

In the drawings the numeral 1 designates a large pipe or casing, preferably having a screen or strainer 2 at its lower end which we will assume is submerged within the water in a well, and the casing has an outlet 3 near its upper end. At suitable and preferably regular intervals throughout the length of the casing it is divided by transverse partitions 4 into compartments or chambers 5 and 6, the former being what I will call the "active" compartments and the latter the "idle" compartments for a reason which will appear below. Secured through each partition and hanging from the same is a tube section 7 having an upwardly opening check valve 8 in its upper

end, and just below this valve the tube section—especially if it be one located within an active compartment—is provided with an outwardly opening relief valve 9. The lowermost partition 4' stands just above the screen or strainer 2 and is provided with a hole through its center, normally closed by a check valve 8' like the rest. The lower end of each tube section stands a little above the check valve in the tube section below as shown. In the casing and opening into the idle compartments are outwardly opening spring-closed relief valves 10. I may here say that these relief valves prevent the trapping of air in the top of each compartment, whereas the relief valves 9 prevent the trapping of air in the upper end of each pipe section, but this will be made clear below.

Passing down throughout the length of the casing and through each of the partitions across the same, is an air pressure pipe 11 whose lower end 12' opens into the lowermost active compartment 5' below the partition which forms the head of the same, and within each of the other active compartments 5 an elbow 12 is connected with the pipe 11 and opens downwardly into the same, the elbow being provided with a rotary valve 13 which when turned for one-quarter of a rotation will close the same to the admission of air. The upper end of the pipe 12 is connected with a compressed air tank 14 wherein pressure is generated by means of a pump or other device indicated at 15, and the details of these elements are unimportant and, therefore they are shown diagrammatically only.

Passing down throughout the length of the casing and preferably at a point opposite the air-pressure pipe 11 is an air-suction pipe 21 whose lower end 22' opens into the lowermost active compartment 5' and whose body is provided with elbows 22 opening downward into the upper portion of each active compartment as shown, and each provided with a rotary valve 23 disposed directly opposite the rotary valve 13 above described. Suction is created within this pipe through a vacuum tank 24 by a pump or other suitable mechanism 25 whose details of construction are not necessary to

describe and which therefore are shown only diagrammatically. Step cocks 26 and 27 are located within the vacuum or suction pipe 21, and similar cocks 16 and 17 in the pressure pipe 11; and these two pipes are connected by a cross pipe 18 having in it a stop cock 28 for a purpose yet to appear. Here again the details of construction are not essential. I might say also at this point that with the exception of those features in this specification whose details are amplified, the specific construction of parts as well as their proportions and materials are not essential to the successful operation of this invention.

Within each active compartment a rock shaft 30 connects the stems of the two valves 13 and 23, and intermediate these valves it passes through the tube section 7 wherein it has an arm 31 carrying a float 32 whose size is less than the interior of said tube so that the passage of water therethrough will not be impeded. The valves at opposite ends of this rock shaft are set quartering to each other, and their disposition with reference to the float is such that when the latter falls it will open the suction pipe and close the pressure pipe, and vice versa.

The operation of this pump as far as has been described is as follows: Assuming that the lower end of the casing is submerged below the water line and that water flows in through the screen or strainer 2 and rises through the lower check valve 8' into the lowermost active compartment 5', as the water rises within the lowermost pipe section (as permitted by the relief valve 9 in the side of the same) the float rises until the valve 13 near the lower extremity 12' of the air pressure pipe 11 is opened and the corresponding valve 23' in the suction pipe is closed. Air pressure admitted through the pipe 11 now flows into the lowermost active compartment 5' and immediately closes the check valve 8'; then pressing on the water within this compartment and outside the tube sections 7, it forces the water up, past the float and the check valve at the head of this tube section, and into the idle compartment 6 above. When the liquid has been driven into said idle compartment, the float is no longer sustained by its buoyancy and drops of its own weight, thereby closing the valve 13 and shutting off the air pressure, and simultaneously opening the valve 23 and connecting the lowermost compartment 5' with the vacuum or suction pipe 21. The result is that instead of pressure within this compartment, the same is now subjected to a partial vacuum, and water is drawn in through the lowermost check valve 8' and the strainer to replenish what has been forced up into the next compartment. I find from experiments made that some of the

charge also goes directly into the second active compartment, caused no doubt by the fact that there is a partial vacuum in the lowermost idle as well as in the second active compartment, and that as soon as the second active compartment has discharged into the second idle compartment, any water that stands higher than the bottom end of the tube in the idle compartment will flow upward into the said second active compartment, caused by the pressure of air trapped in the top of said idle compartment. Each relief valve 10 is to be adjusted so as to allow any surplus air or air above a certain pressure to escape, depending on the pressure in air pipe 11. As the second charge of water enters the lowermost compartment 5' and rises within its tube section, the operation above described is repeated and the valve in the suction pipe 21 is closed while that in the pressure pipe 11 is opened. This action is repeated at points higher and higher throughout the casing, each active compartment drawing the charge of water from the compartment beneath and forcing it throughout its own length and upward into and through the idle compartment next above, where it can be reached by the suction in the active compartment yet farther above. Therefore it will be apparent that the air pressure and the air vacuum need only be carried to a point sufficient to handle the charge in one compartment or at most in two compartments, and a pump composed of a train of said compartments would lift water through an indefinite distance dependent only on the strength of parts.

It sometimes occurs that for one reason or another the float may become stuck or one of its valves may work a little stiff, and the result is that if this defect is not corrected the entire system is put out of use because it is practically impossible—except in very large sized pumps—for an operator to descend through the casing and make repairs. In order, therefore, to provide means whereby this difficulty may be overcome without disrupting the parts of the pump, I make use of the following details: At points within the suction pipe 21 just above its elbows I provide branches 40 whose lower ends are open and project downwardly beneath the partitions which form the heads of these compartments. In each branch is located a small piston 41 which under ordinary conditions is held raised against a stop such as a cross pin 42, and therefore which piston when this pump is working is idle. From the piston a rod 43 projects downward out the lower end of the branch 40 and carries at its lower end a cross head 44 which may be in the shape of a frame 45. The latter is of sufficient size to surround a crank 46 which is formed in the rock shaft 30, and the dis-

- position of parts is such that the cross head never contacts with this crank when the piston is raised and the parts are performing their natural functions. If now the float 5 should become stuck at a high point, the crank at this time is elevated but not to its highest extent. The operator by manipulating the various stop cocks in the air pipes and in the cross pipe connecting them, may 10 shunt or switch the compressed air into the suction pipe 21 so that the latter instead of being a vacuum pipe, now becomes an air pressure pipe. The air rushing down this pipe passes out the branch 40 and depresses 15 the piston 41, which through its rod and cross head gives an impulse to the crank 46 on the rock shaft 30, and the float is started downward within the tube section 7. Immediately the operator reverses the positions 20 of the various stop cocks whereas the dropping of the float reverses the positions of the valves 13 and 23, and the machine resumes its operation as above described. It is true the inrush of compressed air to and 25 through the suction pipe 21 will actuate all the pistons, but no harm is done to the cranks on the rock shafts of such floats as are not stuck. Nor is there a serious interruption to the operation of the pump, be- 30 cause the volume of air admitted through the pipe 21, which otherwise would be a suction pipe, is infinitesimal and hardly more than a puff sufficient to start the crank 46 downward, and the weight of the float will 35 do the rest. I find by experience that the floats will rarely if ever stick at their lowest position—due, no doubt, to the fact that the upward rush of water through the pipe sections prevents.
- 40 What is claimed as new is:
1. In a pump, the combination with an upright casing divided by transverse partitions into a series of compartments, and a downwardly closing check valve in each 45 partition; of two air pipes passing through the length of said casing and having oppositely disposed elbows opening into every other compartment leaving the alternate compartments idle, means for creating air pressure in one pipe and suction in the other, valves in said elbows, a rock shaft to which said valves are connected so that when one is closed the other is opened, and a float connected with said rock shaft for 50 turning the latter by the rise of water, for the purpose set forth.
  2. In a pump, the combination with an upright casing having a series of transverse partitions dividing it into compartments, a 55 tube section hanging from each partition, and an upwardly opening check valve in the upper ends of each tube section; of two air pipes passing through the length of said casing and having elbows at opposite sides
- of said tube section, rotary valves in said elbows, a rock shaft connecting the stems of said valves and passing through said tube section, a float within the latter connected with said rock shaft, and means for creating air pressure in one pipe and suction in the other, for the purpose set forth. 65
3. In a pump, the combination with an upright casing having a series of transverse partitions dividing it into compartments, and a tube section hanging from each partition, each section having an outwardly opening relief valve just beneath the partition which sustains it; of two pipes passing through the length of said casing and having elbows at opposite sides of said tube 75 section, rotary valves in said elbows, a rock shaft connecting the stems of said valves in such manner that when one is open the other is closed, an arm projecting from said shaft within the tube section, a float connected 80 with said arm, and means for creating pressure in one pipe and suction in the other, for the purpose set forth. 85
4. In a pump, the combination with an upright casing having a series of transverse 90 partitions dividing it into compartments, and a tube section hanging from each partition; of two pipes passing through the length of said casing and having oppositely disposed elbows at opposite sides of said tube section, means for creating pressure in one pipe and suction in the other, rotary valves in said elbows, a rock shaft connecting the valves in such manner that when one is open the other is closed, said rock shaft 95 having an elbow within its length, an arm projecting from this shaft within the pipe section, a float connected with said arm, a second elbow projecting from the suction pipe, a piston movably mounted within the 100 upright arm of this elbow, and a cross head connected with said piston and standing above the crank on the rock shaft, for the purpose set forth. 105
5. In a pump, the combination with an 110 upright casing having a series of transverse partitions dividing it into compartments, and a tube section hanging from each partition; of two air pipes passing through the length of said casing and having oppositely disposed elbows at opposite sides of said tube section, rotary valves in said elbows, a rock shaft connecting the valves in such manner that when one is open the other is closed, said rock shaft having an elbow 115 within its length, an arm projecting from this shaft within the pipe section, a float connected with said arm, a branch leading from the suction pipe adjacent each of its elbows and having its lower end standing 120 above the crank in said rock shaft and open, a stop within said branch, a piston slidably mounted in the branch beneath the stop, a 125

rod depending from the piston out the lower end of the branch, a frame on said rod loosely inclosing said crank on the ~~rock~~ shaft, and means for creating air pressure in one pipe and suction in the other, for the purpose set forth.

In testimony whereof I have hereunto set

my hand in presence of two subscribing witnesses.
